(57) **CLAIM**

The ornamental design for a baluster shoe, shown and described.

DESCRIPTION

FIG. 1 is a perspective view of a baluster shoe shown in its intended use of fixing a baluster to a stair railing, with the baluster and stair railing shown in phantom for environmental purposes only and forming no part of the claimed invention;

FIG. 2 is a first side elevation view thereof;

FIG. 3 is a front elevation view thereof;

FIG. 4 is a rear elevation view thereof;

FIG. 5 is a second side elevation view thereof;

FIG. 6 is a top plan view thereof;

FIG. 7 is a bottom plan view thereof with the webbing shown in phantom for illustrative purpose only and forming no part of the claimed invention; and,

FIG. 8 is a perspective view of the baluster shoe.
